Application February 18, 1950, Serial No. 144,944

3 Claims. (Cl. 250—36)

The present invention relates to a circuit-arrangement for producing a sawtooth current in a coil connected to the secondary of a transformer, the primary of which is included in the output circuit of a discharge tube, and more particularly to a circuit-arrangement for the production of sawtooth current wherein the voltage occurring across the secondary of the transformer during the sweep portion of the sawtooth current is rectified and the rectified voltage is made operative in the output circuit of the discharge tube.

In circuit-arrangements of this type it has hitherto been customary to supply to the control grid of the discharge tube a sawtooth voltage, or at least a voltage which increases after the unblocking of the tube which unblocking occurs upon exceeding a given threshold value.

Due to this a very high anode current is produced in the tube and if the tube is a screen-grid tube, the screen-grid dissipation is also excessively high.

The principal object of the present invention is to provide a circuit-arrangement for the production of a sawtooth current wherein a different method of controlling the discharge tube is employed so that maximum anode current is reduced.

Another object of the invention is to provide a circuit-arrangement for producing sawtooth current, wherein screen-grid dissipation of the discharge tube is reduced.

Still another object of the present invention is to provide a circuit-arrangement for the production of saw-tooth currents wherein the physical size of the discharge tube may be minimized.

Further objects of the invention will appear from the following description.

According to the invention, a substantially constant voltage unblocking the tube, which voltage is periodically interrupted by pulse voltages cutting off the tube, is supplied to the control grid of the discharge tube.

In order that the invention may be more clearly understood and readily carried into effect, it will now be described more fully with reference to the accompanying drawing in which:

Figure 1 represents one embodiment of a circuit-arrangement according to the invention,

Figure 2 is a current diagram by means of which the operation of the invention will be explained, and

Figure 3 is a curve showing variation of the control-grid voltage as a function of time.

Referring now to the drawing, and more particularly to Figure 1, there is shown the basic elements of the circuit-arrangement according to the invention for producing a saw-tooth current, comprising a pentode 1, the anode circuit of which includes a primary 2 of a transformer 3. A coil 5 wherein the sawtooth current is produced, and which may be, for example, the deflection coil of a cathode-ray tube is connected to a part of a secondary 4 of transformer 3.

One end of the secondary 4 is connected to the positive terminal of a direct current supply (not shown) which supplies a voltage V_b . The other end of secondary coil

4 is connected to the anode of a diode 6. The cathode of diode 6 is connected both to the end of the winding 2 remote from the anode of pentode 1 and, through a condenser 7, to the cathode of pentode 1.

When the tube 1 is made conductive, the primary 2 of the transformer is traversed by a sawtooth current. During the sweep portion of this current, a voltage having the polarity indicated in the drawing is developed across the winding 4, with the result that the diode 6 becomes conductive and the condenser 7 is charged. This condenser is charged to a voltage approximately equal to the sum of the voltages of the direct current supply V_b and the voltage occurring across the winding 4 during the sweep portion of the sawtooth current, so as to form a source of direct current supply of considerably higher voltage.

If the control at a control grid 8 of the pentode is effected by means of a sawtooth voltage by which the pentode is unblocked on exceeding a given negative bias, the current curves shown in Fig. 2 occur as a function of time.

The tube 1 is traversed by a current I_a as shown by the curve 9 of Fig. 2. This current has a maximum value $I_{a(\max)}$. The sawtooth current traversing coil 5, shown in curve 15 of Fig. 2, varies between the values $-I_1$ and $+I_2$, the value $I_1 + I_2$ being equal to $2 I_{\max}$ if $I_{\max}$ represents the amplitude of the sawtooth current.

From Fig. 1 it appears that the voltage E_s across the primary of the transformer is determined by

$$30 \quad E_s = \frac{V_b - V_a}{1 - n}$$

where n represents the transformation ratio of the transformer.

From Fig. 2 it follows that:

$$35 \quad I_{a(\max)} = 2 I_{\max} \times \frac{1+K}{1+\sqrt{\eta}}$$

if

$$40 \quad 1+K = \frac{I_{a(\max)}}{I_2}$$

and

$$\eta = \frac{(I_1)^2}{(I_2)^2} = \text{efficiency of coil plus transformer}$$

45 From both expressions it follows that:

$$I_{a(\max)} \times (V_b - V_a) = 2 I_{\max} \times E_s \times \frac{(1-n)(1+K)}{1+\sqrt{\eta}} \quad (1)$$

50 In order to make the left-hand member of (1) as small as possible:

1. K should be as small as possible which means that $I_{a(\max)}$ should practically not exceed I_2 ,

2. The efficiency η should be made as high as possible by rendering coil 5 and transformer 3 as free as possible of losses.

3. The transformation ratio should approach as closely as possible to unity. To this end the pentode 1 should be controlled in a definite manner.

60 Since, in the circuit shown in Fig. 1, the two transformer windings are connected in series through the diode 6, and because the average primary and secondary currents should be equal to one another and because a further relation exists between the ampere turns in the two windings in connection with the sawtooth current supplied to coil 5, the transformation ratio n should not be chosen arbitrarily.

From this condition we may deduct the relation

$$70 \quad n = \frac{a+\eta}{a+1+\eta} \quad (2)$$

where

$a = \frac{O_3}{O_2}$ = ratio of the areas shown in Fig. 2 in the current diagram

and

$b = \frac{I_x}{I_a}$ = relative current loss which occurs in the condenser 7 shown in Fig. 1

I_x being the current leaking from condenser 7.

When it is desired that the transformation ratio should approach unity, a should be made as high as possible which means, as appears from Fig. 2, that the pentode should be controlled in such manner that the average anode current I_a approaches as closely as possible the maximum anode current $I_{a(\max)}$.

This is ensured by supplying the control grid of the pentode with a control voltage varying with time as shown in Fig. 3.

During the sweep portion of the sawtooth current traversing coil 5 in Fig. 1, a substantially constant unblocking voltage V_g is available at the control grid 8, which voltage may, for example, be equal to the cathode potential of the pentode. During the fly-back, the tube 1 is cut off by a pulse voltage.

If the circuit-arrangement shown in Fig. 1 does not self-oscillate but is, for example, controlled by a preceding blocking oscillator, the negative voltage pulses appearing across the anode of the tube of the blocking oscillator may be supplied to the control grid of the pentode 1. The circuit-arrangement shown in Fig. 1 is self-oscillatory. To this end a positive feedback path is provided between a tapping 10 on the secondary of the transformer 3 and the control grid 8 of the pentode 1. This feedback path comprises a blocking condenser 11 and a resistance 12, which is preferably a variable resistor. Across the secondary 4 of the transformer 3 a voltage is produced, the form of which corresponds to the desired control-grid voltage, so that this voltage may be supplied to the control grid. The control grid 8 is connected to the cathode through a leakage resistance 13. Synchronisation signals may be supplied to the grid 8 by means of a condenser 14.

The frequency of the sawtooth oscillator can be controlled by varying the resistance 12.

From the Expressions 1 and 2, developed hereinbefore, it follows that:

$$I_{a(\max)} \times (V_b - V_a) = \frac{(1+b-\eta)(1+K)}{(1+b+a)(1+\sqrt{\eta})} \times 2I_{\max} \times E_s$$

where the factor

$$\frac{1+K}{1+b+a}$$

is determined by the method of controlling the pentode.

In the known method of control, the value of this factor is approximately 0.8 to 0.9, whereas the use of the circuit-arrangement according to the invention permits a value lower than 0.4 to be attained. Owing to this, a stronger sawtooth current can be obtained with a materially lower pentode load.

While we have described our invention in a specific use thereof and in a specific embodiment, we do not wish to be limited thereto, for obvious modifications will occur to those skilled in the art without departing from the spirit and scope of the invention.

We claim:

1. A circuit-arrangement for generating a sawtooth current, comprising an electron discharge tube having a cathode, a control grid and an anode, an input circuit intercoupling said cathode and said control grid, an output circuit intercoupling said cathode and said anode, a transformer having a primary and a secondary winding, said primary winding being included in said output circuit, means to apply a positive potential to one end of said secondary winding, an output coil coupled in parallel with a portion of said secondary winding, means to apply a substantially constant potential to said input circuit to render said tube conductive thereby producing a voltage in said secondary winding and a current flow in said output coil, a capacitive element interposed in said output circuit between said primary coil and said cathode, a rectifier element coupled to the other end of said secondary winding and to said output circuit between said primary winding and said capacitive element to rectify said voltage, and apply the rectified voltage to said output circuit, and means to apply a pulse voltage to said input circuit periodically to render said tube nonconductive thereby to arrest current flow in said output coil.

2. A circuit arrangement, as set forth in claim 1, wherein said means to apply a pulse voltage to said input circuit is constituted by feedback means intercoupling said secondary winding to said input circuit.

3. A circuit arrangement, as set forth in claim 2, wherein said feedback means includes a condenser connected in series with a resistor between a point in said secondary winding and said grid.
